CLAIM

The ornamental design for lock for an automobile pedal, as shown and described.

DESCRIPTION

FIG. 1 is a front elevational view of lock for an automobile pedal showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The broken-line depiction of a brake pedal and portion of floor in FIGS. 3 and 4 is for illustrative purposes only and forms no part of the claimed design.

*FIG. 1.**FIG. 2.*

FIG. 3.

FIG. 4.

FIG. 5.

FIG. 6.
